FOLDING TABLE AND SEAT ASSEMBLY

Julius J. Schrader, Hoisington, Kans.

Application August 26, 1954, Serial No. 452,277

4 Claims. (Cl. 155—124)

This invention relates to a folding picnic table and more specifically provides a foldable table and seat assembly wherein the table and the seats are so interconnected as to be compactly folded into a relatively small package.

An object of this invention is to provide a folding picnic table including a table top and seats arranged alongside, wherein the device is positively locked in extended position and in folded condition wherein the picnic table may be easily carried to a desired location and quickly and easily set up for operation.

Another object of the present invention is to provide a picnic table of the average dinner table size wherein persons may be seated at the table without encountering obstructions and the table may be only partially unfolded or completely unfolded, as desired, thereby providing a versatile type of folding picnic table.

Still another important object of the present invention is to provide a folding picnic table that will provide a table space for a plurality of persons and yet be folded into a compact condition for easy carrying wherein the device is especially useful for tourists or vacationers as the same may be reduced in size for enabling it to be stored within the trunk of an automobile and readily set up for use when desired.

Still other important features of the present invention include its simplicity of construction, sturdiness in unfolded position, its adaptation for many and varied purposes, and its relatively inexpensive manufacture.

These together with other objects and advantages which will become subsequently apparent reside in the details of construction and operation, reference being had to the accompanying drawings forming a part hereof, wherein like numerals refer to like parts throughout, and in which:

Figure 1 is a side elevational view showing the folding table of the present invention in extended or unfolded position;

Figure 2 is an end elevational view showing the relation between the table top, seat members and the folding supports for each of the components of the invention;

Figure 3 is an end view showing the picnic table of the present invention in folded position;

Figure 4 is a side elevational view showing the first step in unfolding the table, wherein the table tops are positioned in longitudinal alignment and the supporting legs folded downwardly therefrom;

Figure 5 is an end elevational view showing the construction of Figure 4 wherein the seats are still in unfolded position;

Figure 6 is a side elevational view of the structure of Figure 3 wherein the table is in its completely folded position;

Figure 7 is a transverse, bottom plan view taken substantially upon a plane passing along section line 7—7 of Figure 4 showing the details of construction of the latch means for the table legs and the catch for retaining the seats in folded position;

2

Figure 8 is a detailed view showing the table leg locking means in locking position;

Figure 9 is a transverse, vertical sectional view taken substantially upon a plane passing along section line 9—9 of Figure 7 showing further structural details of the leg locking means for the table and seat; and

Figure 10 is a detailed transverse, vertical sectional view taken substantially along a plane passing along section line 10—10 of Figure 7 showing the details of construction of the latch for retaining the seat in collapsed position under the table top.

Referring now specifically to the drawings, it will be seen that the numeral 10 generally designates the folding picnic table of the present invention including a pair of table top members 12 and 14 hingedly secured together in end-to-end relation by a hinge pin 16 that interconnects downwardly angulated lugs 18 secured to each of the table top members 12 and 14 wherein the table top members 12 and 14 will be positioned in spaced parallel positions when in their collapsed position, substantially as illustrated in Figure 3.

Positioned at each end of each table top member 12 and 14 is an inverted U-shaped member 20 having a smaller inverted U-shaped member 22 nested therein wherein the depending legs of the U-shaped members 20 and 22 form spaced legs for pivotally receiving the upper ends 24 of a pair of depending legs 26 that are secured together at their midpoints and extend outwardly at their lower ends, as designated by the numeral 28, for providing a supporting area for the table top members 12 and 14. It will be seen that each end of the table top members 12 and 14 is provided with supporting legs 26 and the outwardly extending portions 28 form an area of support substantially equal to the area of the table top members 12 and 14 and the legs 26 pivot inwardly towards each other about hinge pins 30 wherein the legs 26 will overlie each other in spaced parallel relation.

Each of the table top members 12 and 14 is provided with a pair of seat members 32 that are the same length as the table top members 12 and 14 and having adjoining abutting edges when in the unfolded position. Each of the seat members 32 is provided with a pair of inverted U-shaped members 34 and 36 on the undersurface thereof, thereby providing spaced lugs for pivotally securing a U-shaped supporting leg 38 on hinge pin 40. A supporting leg 38 is pivotally secured to each end of each supporting seat 32 and the inner lower corner of each leg 38 is pivotally secured to the outwardly extending portions 28 of the table supporting legs 26 by elongated connecting links 42 wherein the seats 32 may be pivoted and swung upwardly into a position closely adjacent to and underlying the side edges of the table top members 12 and 14. The supporting legs 38, the connecting links 42 and the table supporting legs 26 all pivot inwardly simultaneously as the supporting legs 38 and the supporting legs 26 pivot on hinge pins 30 and 40 that are in alignment with each other when the seat members 32 are folded into a position underlying the table top members 12 and 14. A connecting link 44 may interconnect the lower adjoining ends of the table supporting legs 26 for reinforcing the table supporting leg structure, as desired.

Referring now specifically to Figure 10, it will be seen that each table top section, as designated by the numeral 12, is provided with a Z-shaped bracket 46 positioned on the undersurface thereof along the transverse center line, and the Z-shaped bracket is provided with an aperture 48 in the end spaced from the undersurface of the table top 12 for slidably receiving the seat member 32 between the portion of the bracket 46 spaced from the

table top 12 and the undersurface of the table top 12. An elongated pivotal catch 50 is pivotally secured between depending lugs 54 mounted on the undersurface of the seat member 32 and the catch 50 is provided with an upturned hooked end portion 56 for engaging the aperture 48 in the bracket 46 for retaining the seat member 32 in folded position beneath the table top 12. The outer end of the pivotal latch 50 is provided with an enlarged portion 58 for forming a finger engaging portion for releasing the hooked end 56 from the aperture 48, thereby permitting the seat member 32 to be withdrawn from beneath the undersurface of the table top 12. It will be understood that each of the seat members 32 and table top members 12 and 14 is provided with the interlocking bracket 46 and latch 50 for retaining the seat members 32 in folded position beneath the undersurface of the table tops 12 and 14, thereby securing and positioning the side edges of the table tops 12 and the seat members 32 in coextensive and underlying relation. After the seat members 32 have been positioned in their folded positions, the leg members 38 and the leg members 26 may be pivoted inwardly to a position substantially as shown in Figures 3 and 6, wherein all of the leg members 38 and 26 and all of the table top members are positioned in overlying parallel relation.

In order to secure the table supporting legs 26 and the seat supporting legs 38 in extended position in perpendicular relation to the table top surfaces 12 and 14 and the seats 32, respectively, automatic locking means is provided which will lock the legs in perpendicular relation when the seats 32 are withdrawn from under the table top surfaces 12 and 14 and the locking means will be automatically disengaged when the seats 32 are folded to their retracted position, thereby permitting easy folding of the supporting legs 26 and 38. The locking means is provided at each end of each seat 32 and each table top surface 12 and 14, and for the purposes of explanation, a single locking means will be described, with the understanding that a similar lock is provided at each end of each seat 32 and table top surface 12 and 14.

Referring specifically to Figures 7, 8 and 9, it will be seen that each of the depending legs of the U-shaped brackets 20 and 22 on the table top 12 and the U-shaped brackets 34 and 36 on the seats 32 are provided with aligned apertures 60 and 62 with the apertures on the inner U-shaped members 22 and 36, respectively, being larger than the apertures on the outer brackets 20 and 34. The upper ends of each of the supporting legs 26 and 38 are provided with a transverse aperture 64 that is tapered with the larger ends adapted to align with the larger aperture in the inner brackets 22 and 36 on the supporting leg 26 and the supporting leg 38 adjacent the supporting leg 26 and on the outer bracket 34 remote from the supporting leg 26, the aperture 62 is provided on the outer bracket 34 and the aperture 64 in front of the leg 38 communicates therewith. A pivotal member 66 is secured to the undersurface of the table top 12 by pivot pins 68 and the outer end of the pivot member 66 is provided with a tapered pointed projection 70 which is substantially the same shape as the apertures 60 in the depending lugs 20 and 22 and the aperture 64 in the leg 26 for engagement therewith for locking the leg 26 in perpendicular relation to the table top surface 12. A tension coil spring 72 is provided between the pivot member 66 and the table top surface 12 for continuously urging the projection 70 into the apertures 60. The outer end of the pivot member 66 is provided with a projecting portion 74 which is in spaced relation to the undersurface of the table top 12 for receiving the inner edge of the seat 32 and this offset portion 74 is provided with a depending abutment 76 for engagement by a depending abutment 78 on a sliding bracket 80 having a pair of longitudinal apertures 82 therein for receiving fastening means 84. The sliding bracket 80 is provided with a pair of projecting lugs 86 having extending tapered projections 88 thereon

for engagement with the apertures 62 in the U-shaped members 34 and 36 and engagement with the aperture 64 in the upper end of the legs 38. A tension spring 90 is secured at one end to a bracket 92 on the undersurface 5 of the seat 32, and at its other end to a projecting lug 94 on the sliding bracket 80, thereby continuously urging the bracket 80 towards the inner edge of the seat 32 and continuously urging the tapered projections 88 into engagement with the apertures 62 in the U-shaped members 34 and 36 and the aperture 64 in the upper end of the leg 38. The abutments 76 and 78 engage each other when the seats 32 are moved into a position under the table tops 12 thereby urging the projection 70 out of engagement with the apertures 60 in the U-shaped members 20 and 22 and the aperture 26 in the table top supporting leg 26 and also retracts the projections 88 on the bracket 80 from engagement with the apertures 62 in the U-shaped members 34 and 36 and from engagement with the apertures 64 in the upper end of the U-shaped leg 38, thereby 15 permitting the U-shaped legs 38 and the legs 26 to be collapsed to a position underlying the table top surfaces 12 and the seats 32, respectively.

It will be seen that the operation of the locking projections 70 and 88 will be automatic in that they will be 20 released when the seat members 32 are positioned under the table top surfaces 12 and 14 and they will automatically be urged into engagement when the seat members 32 are retracted from underneath the table top surfaces 12 and 14, after the pivotal catch 50 has been released.

It will be seen that the present invention may be easily 25 and quickly extended or folded and provides a table top area of adequate size to accommodate several persons and may be quickly collapsed into a relatively compact position for storage in any suitable place, such as a trunk of an automobile, or the like. Obviously, the device may 30 be constructed of any suitable materials having the necessary qualities of lightness, rigidity and strength. The unique locking means for retaining the table of the present invention in extended position provides a sturdy and rigid 35 table structure for providing a secure support for articles placed thereon, and the seats 32 form a secure and rigid support for persons employing the table.

From the foregoing, the construction and operation of the device will be readily understood and further explanation 40 is believed to be unnecessary. However, since numerous modifications and changes will occur to those skilled in the art, it is not desired to limit the invention to the exact construction shown and described, and accordingly, all suitable modifications and equivalents may 45 be resorted to, falling within the scope of the appended claims.

What is claimed as new is as follows:

1. A folding table and seat assembly comprising a 50 pair of table tops which are arranged to be coplanar when the table is in the open position and superposed when the table is folded, a hinge connecting said tops to each other, means to support each table top in the open position and including for each top a pair of legs, means pivotally securing said legs to its table top so 55 that said legs are swingable to a position to support said top and to a position where they are folded under said top, a pair of seats, seat legs pivoted to said seats for movement to a position to support the seats and to a position nested under the seats, and connecting links pivoted to said seat legs and the legs of the table top to 60 constrain the seats to move pivotally from a position near to its top to a position nested thereunder and to require the seat legs and table legs when pivotally moved to be 65 actuated in unison, said connecting links automatically holding said seat legs in the extended position when the seats are pivoted away from their table top.

2. The folding table of claim 1 wherein there are 70 catches operatively connected with said seats and said table tops in order to hold said seats releasably fastened

to their tops when the seats are moved to a superposed position with respect to said tops.

3. The folding table of claim 1 wherein there are means operatively connected with said seat legs and seats to automatically lock said seat legs in the extended position when said seats are withdrawn from beneath said table tops.

4. The folding table of claim 1 wherein there are means operatively connected with said seat legs and seats to automatically lock said seat legs in the extended position when said seats are withdrawn from beneath said table tops.

table tops, and there are means on the table tops and the legs thereof to automatically lock the latter legs in the extended position when the last-mentioned legs are withdrawn from their table tops.
